UNITED STATES PATENT OFFICE.

GEORGE W. PACKER, OF CHICAGO, ILLINOIS, ASSIGNOR TO THE DEERING HARVESTER COMPANY, OF CHICAGO, ILLINOIS.

MACHINE FOR FINISHING TONGUES.

SPECIFICATION forming part of Letters Patent No. 702,671, dated June 17, 1902.

Application filed March 23, 1900. Serial No. 9,900. (No model.)

To all whom it may concern:

Be it known that I, GEORGE W. PACKER, of Chicago, in the county of Cook and State of Illinois, have invented certain new and useful Improvements in Machines for Finishing Tongues and Similar Purposes, of which the following is a full description, reference being had to the accompanying drawings, in which—

Figure 1 is a plan view; Fig. 2, a side elevation; Fig. 3, a side elevation of the machine in section; Fig. 4, a front view; and Figs. 5, 6, 7, 8, 9, 10, and 11 are details.

The object of the machine of my invention is to finish vehicle-tongues after they have been sawed from the plank.

In manufacturing tongues it is customary to dress all sides of a plank of proper thickness and wide enough to make two tongues in the ordinary planing-machine and then saw diagonally, so as to give each the proper taper. So prepared they are then passed through my machine, which finishes the sawed sides and corners or rounds the four corners or a part of them, as well as the other side, as may be desired.

The principle of the machine will best be understood by first referring to Fig. 3, in which A is the main supporting-frame. It is made of two counterparts joined by the stay-rods $a a a$ and a' . a^2 forms a portion of the bed over which the tongues move while being operated upon. It is secured to the side frame-pieces A by the bolts a^3 , which pass through a slot in downward-reaching extensions at each end. Secured, as it is, by bolting through slots, it may be raised or lowered to adjust it to proper height. Upon this, as shown, is the roller a^4 , its surface being slightly above the upper surface of a^2 . Upon the support a^2 are the adjustable guides a^5 , between which the tongue to be operated upon passes.

B is a feed-roller adapted to move the tongue over the planing-head B'.

b and b' are guides similar to those a^5 and a^5' , their purpose being merely to hold the tongue in proper position. It is thus seen that the tongue is only supported when first entered on the roller a^4 and the feeding-roller B.

C is a presser or roller supported upon the arms $c c$. These arms pass downwardly one upon each side of the space provided for the

tongue to pass and are connected to the piston-rod c' , which passes upward from the compressed-air cylinder C'. The air-cylinders are connected to a main reservoir by the pipe D. The admission of compressed air into the cylinder is controlled by a tripping device made operable by the material to be acted upon and has the effect of moving the roller C downward, so as to press upon the tongue. It is found best to give the roller C its pressure by means of the air-cylinder, for the reason that whatever the taper of the tongue the roller can follow it and substantially the same pressure be maintained, which would not be the case if moved by a spring. In its normal position the roller is elevated, as shown in Fig. 3.

Upon a rock-shaft E is the arm e of the tripping device, and extending from it horizontally is the arm e' .

c^2 is a three-way air-valve, which is connected by the rod c^3 to the arm e' . Upon passing the tongue into the machine it engages the arm e on the rock-shaft E and moves it downward, thus opening the valve c^2 and admitting air into the cylinder C', which forces the roller C downward. Thus introduced the tongue is firmly held and by the operation of the feeding-wheel B is moved over the planer-head B'.

F and F' are chamfering cutter-heads, one above and the other below the tongue-passage. The bottom surface of the tongue moves upon a horizontal plane, and the chamfering-head F is so supported that it may move downward with the taper of the tongue as the latter passes through the machine. It is also essential that the chamfering-head F' rise at the proper time while the tongue is passing through. Both these are accomplished in the following manner: The cutter-head F is upon a shaft journaled in the arm f , which is pivoted to the upreaching arms G of the main frame. The cutter-head F' is upon a shaft journaled in the arm f' , pivoted at G' near the base of the upreaching arms to the main frame.

Upon the vertical shafts H and H', suitably journaled in the main frame, are the vertical rollers H' and H', placed upon each side of the path of travel of the tongue. These shafts are journaled below in the bearings $h h$, which are bolted to the cross-bar h' by bolts passing

through slots in a cross portion of the main frame. By means of these bolts and slots the journal-bearings may be adjusted from each other and held there. Near the top of the frame are the bearings h^2 h^3 , supported in the cross-bar of the frame h^3 . The journal-bearings are provided with a collar above this bar and with a nut h^4 below. This provides for adjustment of the upper ends of the shafts, so that the rollers H' may be placed a proper distance apart so as to engage the tongue with sufficient pressure to draw it through the machine after its last end has passed the feeding-roller B. These two shafts last mentioned are geared together, as shown in Fig. 1, by the gears h^5 h^6 . Upon the shaft is also the worm-wheel h^6 , and journaled in the main frame is a worm-shaft h^7 . Upon this latter shaft is the pulley h^8 .

The above-mentioned rotary parts, to which power is imparted, are given motion in the following manner: Suitably supported above the machine may be placed counter-shafts over which the belts 1, 2, and 3 are supposed to be thrown. The belt 1 passes around the pulley I on the cutter-head shaft and gives the latter rotation in the proper direction. The belt 2 passes around the pulley J upon the shaft J'. Upon the shaft J' is also the pulley j. Over the pulley j and over the pulley f^4 on the shaft f^3 the belt j' is thrown. By means of this the chamfering-head F' is given rotation. Upon the shaft J' is also the pulley J^2 , and upon the shaft K, suitably journaled on the frame, is the pulley K'. Over the pulleys K' J^2 is thrown a half-twist belt k. The shaft K is thus given rotation, and through it the feeding devices move. Upon the shaft K is the sprocket-wheel k', and upon the shaft L is the sprocket-wheel l, to which the feeding-wheel B is secured. Over the two sprocket-wheels a chain is thrown, and thus movement imparted to the feeding device B, first to act upon the tongue. Upon the shaft K is a pulley k^2 , and around it and the pulley h^8 is thrown a belt h^9 . By this means movement is imparted to the feeding-rollers H' H' , last to act upon the tongue. Upon the shaft G is also the driving-pulley G^2 , which takes the belt 3. The pulley G^3 is upon the shaft G. Upon the arm f is placed the pulley f^5 . Around the latter two the belt f^6 is thrown.

Referring now to Fig. 9, the mechanism for moving the chamfering-head-supporting arms f f' will be best understood. N is a rock-shaft passing from one side to the other of the frame of the machine and suitably journaled therein. N' is also a rock-shaft passing from one side to the other of the machine and suitably journaled in the main frame. Upon the rock-shaft N is the cam n, upon which an antifriction-roller n' on the end of the arm f' rests. n^2 is a downwardly-reaching arm suitably secured to the shaft N, into an eye in which the spring O is hooked. The said spring is also connected to the cross-bar

a' of the main frame. P is an air-cylinder connected by pipes to the main supply-pipe D', the latter being provided with the valve p . The cylinder is provided with the usual piston and rod. The purpose of the spring O is to hold the cam in the position shown in Fig. 3.

The device next to be described may be better understood by reference to Fig. 6, in which the cylinder P and various pipes, links, and levers are shown; but for clearness the pipes are shown broken, and the cylinder is placed on the same horizontal plane as the pipes. P' is a roller upon the arm p' , pivoted to a suitable part of the frame at p^3 . The lever extends beyond the pivot and is connected at p^3 to the link p^4 . This link is connected at p^5 to the arm p^6 of the valve p . Normally the roller p' is in the position shown in full lines in Fig. 6; but if the butt of the tongue comes against it, it, the lever, the links, and the three-way valve-lever p^6 are moved to the positions shown by dotted lines. The effect of this is to open the three-way valve p and permit exhaust of the air in the cylinder P. This leaves the piston at the lower end of the cylinder. The purpose of the cylinder P and its piston and rod, let it be understood, is to move the chamfering-heads to and from each other as required, as will now be explained.

The tongues to be chamfered in this machine are by the processes of working them out of the plank planed upon what will be three sides. They are then fed into this machine butt first from the right hand as the machine is seen in Fig. 3. As they are passed inward the butt strikes the arm e of the tripping device, and through the connection e^3 the three-way valve c^2 is so moved as to admit air into the top of the cylinder C'. Through the piston-rod and the upreaching arms c c the roller C is brought down upon the tongue, and the feeding-wheel passes the latter along over the planer-head B'. The butt of the tongue striking the roller p' causes the three-way valve p to open and permit the air in the upper end of the cylinder to exhaust. The tongue then passes onward, its remaining rough side being dressed in the meantime, until it engages the roller R. (See Figs. 3 and 6.) The tongue that the machine as shown is adapted to work is left unchamfered for some distance from its butt-end, and the roller R is the same distance from the chamfering-heads as that from the butt of the tongue to the point where the chamfer is intended to begin.

S is a two-way valve and has an arm or tip s adapted to open and close the same. s' is a spring connected to the said arm and to the main frame in such a manner as to bring the levers and links connected thereto to the position shown in full lines.

s^2 is an arm adjustably connected to the main frame and to the arm s by the link s^3 . When the butt of the tongue reaches the roller R on the arm s^2 , the parts moved to

the position shown by dotted lines in Fig. 6. In short, the movement of the arm having the roller R to the position shown opens the valve S and permits the compressed air to pass into

5 the cylinder P. The movement of the piston-rod outward actuates the bell-crank T, which is pivoted to the main frame, and by means of the link t the arm f is moved down, and with it the cutter-head F. The same 10 movement of the piston-rod through the instrumentality of the link t rocks the cam n upon its support N, and the arm f', having the antifriction-roller n' thereon, is moved upward simultaneously with the downward 15 movement of the upper chamfering-head. The proportions given to the cam and its arm and the bell-crank T are such as to move the two chamfering-heads together at the proper rate. The chamfering-heads F and F' are 20 made in two parts in the present instance, as it is not desired to chamfer the tongue to the middle line, and the space between them, F'', is taken advantage of and the guide f² extended between. This is suitably secured to 25 the arm f by means of a bolt, so as to be adjustable vertically. The arms f and f', although, as one piece, are, in fact, of two parts; but this is not essential. The cutters of the 30 chamfering-head F are allowed to extend a little below the lower surface of the guide f². This prevents the said chamfering-head from jumping downward into the material being operated upon. In order to move the roller C upward as soon as the air is permitted to 35 pass from the cylinder C' through the three-way valve c', a counterpoise-weight U is used. This weight is upon a lever of the first kind, which has its fulcrum upon a stand u, extending from the floor and connected to the 40 piston of the cylinder C'.

V is a roller for sustaining the tongue while passing out of the machine.

If the machine is used for the purpose of 45 chamfering only one side or edge of a tapering part, the upper chamfering-head may be removed, and if it is desired to chamfer all corners of a piece of timber the lower cutter-head may be fixed at proper height by any suitable means.

50 It is plain that this machine might be turned upon its side, and, suitably supported, still operate precisely the same as now except that the weight U would have to be connected to the piston-rod c' in such a manner 55 as to move the latter horizontally instead of vertically. When I speak in the claims of locating one cutter above the piece to be operated upon and one below, I must be understood as referring to placing them so as to act 60 in opposition merely. The terms "upper" and "lower" will be used only because they correspond with the machine as shown in the drawings.

The relative positions of the roller C and 65 the feeding-roller B may be reversed, if desired. The roller C, in fact, may be omitted, as it serves merely as an antifriction device.

A smooth-surfaced block would serve an equivalent purpose, except that it would offer more resistance to the passage of the material being operated upon.

70 From the construction described it is clear that the chamfering cutter-heads can be moved simultaneously into their working position, and by a proper shaping of the cam n 75 the lower cutter-head can be raised to and held in any desired or definite position while the upper cutter-head is moved gradually toward it during the cutting operation.

What I claim as my invention, and desire 80 to secure by Letters Patent, is—

1. In a machine for operating upon the sides and edges of tapering pieces, two cutting-heads, one arranged above and the other below the path of the material to be acted upon, 85 mechanism for operating said cutting-heads, fluid-operated means independent of said mechanism for holding said cutting-heads above and below the path of the material and for positively moving said cutting-heads to 90 ward each other to act upon said material, and a trip for admitting the fluid to operative relation with said means, said trip being located beyond the cutting-heads to be engaged and actuated by the material after a predetermined length of said material has passed 95 the cutting-heads whereby said means is caused to operate to move the cutting-heads toward each other.

2. In a machine for operating upon the sides 100 and edges of tapering pieces, two cutting-heads, one arranged above and the other below the path of the material to be acted upon, mechanism for operating said cutting-heads, fluid-operated means independent of said 105 mechanism for moving said cutting-heads toward each other and for yieldingly holding them in operative relation to the material to be acted upon, and a trip for admitting fluid into operative relation to said means, said 110 trip being located beyond the cutting-heads to be engaged and actuated by the material after a predetermined length has passed the cutting-heads, whereby said fluid-operated means is caused to operate to move the cutting-heads toward each other and yieldingly hold them in operative position.

3. In a machine of the character described, a feeding device, a presser adapted to act in opposition thereto and means made operative 120 by the material being placed in the machine, for moving the presser upon said material, supports and passage-ways for the material being acted upon, a cutting-head, means for holding said cutting-head out of the path of the material until a predetermined length has been fed past the cutting-head and for thereafter moving said cutting-head into operative relation to said material, and a trip for said means located beyond the cutting-head in the path of the material to cause said means to become operative to act on a part 125 only of said material.

4. In a machine for the purpose described,

supports and passage-way for the material to be operated upon, a cutting-head, means for holding said cutting-head out of the path of the material and for positively lowering the cutting-head as required, and a trip for said means located beyond the cutter-head in the path of and to be actuated by the material after a predetermined length has passed the cutting-head to cause said means to operate and positively lower the cutting-head to act on a part only of said material.

5. In a machine for the purposes described, one or more cutting-heads, a feeding-roller adapted to operate upon one side of the wood or other material operated upon, a pressing-roller upon the opposite side thereof, mechanism for forcing said pressing-roller against the material operated upon, in combination with a tripping device, controlled by the material to be operated upon, whereby the latter is thus held against the said feeding-roller, all combined, substantially as described.

6. In a machine for the purposes described, a feeding-roller, a presser to force the material being operated upon against the said feeding-roller, tripping mechanism operated by the material to be acted upon to actuate the said presser and thus cause it to force the material being operated upon against the feeding-roller, a planing-head adapted to plane the under surface of the material being operated upon, and a chamfering-head adapted to operate upon the said material, all combined, substantially as described.

7. In a machine for the purposes described, a feeding-roller, a presser adapted to act in opposition thereto, a tripping device adapted to be actuated by the material being placed in the machine, and thus cause the presser to force the material against the feeding-roller, and to press downward upon tapering material operated upon, as it passes through the machine, all combined, substantially as described.

45. In a machine for the purposes described, a feeding-roller, a presser adapted to act in opposition thereto, a tripping device adapted to be moved by the material being placed in the machine, and thus cause the presser to force the material against the feeding-roller, and to press downward upon any tapering piece of material operated upon, as it passes through the machine, a cutting device adapted to act upon the said tapering material being operated upon, and mechanism for causing it to follow down the incline of said taper, all combined, substantially as described.

9. In a machine for the purposes described, a cutting-head, a feeding-roller, a presser normally held in such position as to permit the entrance of the material to be operated upon, and the tripping device, in combination with the air-pressure cylinder and its mechanism, suitably connected to the said presser, all combined, substantially as described.

10. In a machine for the purposes described, a support and passage-way for the material to be operated upon, cutting-heads above and below said passage-way, an air-pressure cylinder, provided with suitable valves and piston, the latter connected to said cutting devices and adapted to move them, and mechanism adapted to cause air to be admitted to the said cylinder and the said heads thus be forced to position to operate, substantially as described.

11. In a machine for the purposes described, a support and passage-way for the material to be operated upon, a cutting device below said passage-way movably supported upon the main frame, a cutting device above said passage-way, also suitably supported upon the said main frame, mechanism adapted to raise the cutting device located below the line of said supports and passage-way, and maintain it in a definite position, said cutting device that is located above said supports and passage-way adapted to be moved gradually downward during the passage of any tapering piece being operated upon, all combined, substantially as described.

12. In a machine for the purposes described, a support and passage-way for the material to be operated upon, a cutting device below said passage-way movably supported upon the main frame, a cutting device above said passage-way, also suitably supported upon the said main frame, mechanism adapted to raise the cutting device that is located below the line of said supports and passage-way, and maintain it in a definite position, said cutting device that is located above said supports and passage-way adapted to be moved gradually downward during the passage of the tapering piece being operated upon, and means in common for moving the said cutting devices to their work, said means adapted to move the lower one to a definite position, and permit the upper one to act in a constantly-varying position, all combined, substantially as described.

13. In a machine for the purpose described, a support and passage-way for the material to be operated upon, a cutting device located below said passage-way and movably supported upon the main frame, a cutting device located above said passage-way and also suitably supported upon the main frame, and mechanism for moving said cutting devices toward each other and thereafter for maintaining the cutting device located below the passage-way in a definite position and continuing the movement of the cutting device located above the passage-way toward the cutting device located below the said passage-way.
